(57) **CLAIM**

The ornamental design for a lawn and paver edging, as shown and described.

DESCRIPTION

FIG. 1 is a perspective view of a lawn and paver edging showing our new design;

FIG. 2 is a top plan view thereof;

FIG. 3 is a bottom plan view thereof;

FIG. 4 is a left side elevational view thereof, the right side elevational view being a mirror image thereof;

FIG. 5 is a front elevational view thereof;

FIG. 6 is a rear elevational view thereof; and,

FIG. 7 is a top plan view thereof, showing the lawn and paver edging in an alternate configuration.

The broken lines in the drawings depict portions of the article that form no part of the claim.

The drawings are shown with a symbolic break in their length. The appearance of any portion of the article between the break lines forms no part of the claimed design.
